(57) **CLAIM**

The ornamental design for a circus elephant water toy, as shown and described.

DESCRIPTION

FIG. 1 is a perspective view of a circus elephant water toy of the applicant's design;

FIG. 2 is a left side view of FIG. 1;

FIG. 3 is a right-side view of FIG. 1;

FIG. 4 is a top view of FIG. 1;

FIG. 5 is a bottom view of FIG. 1;

FIG. 6 is a front side view of FIG. 1;

FIG. 7 is a back side view of FIG. 1;

FIG. 8 is a perspective view of an exploded circus elephant water toy of the applicant's design;

FIG. 9 is a left side view of FIG. 8;

FIG. 10 is a right-side view of FIG. 8;

FIG. 11 is a top view of FIG. 8;

FIG. 12 is a bottom view of FIG. 8;

FIG. 13 is a front side view of FIG. 8;

FIG. 14 is a back side view of FIG. 8; and,

FIG. 15 is an enlarged view of the selected portion in FIG. 8.

Broken lines are included for the purpose of illustrating portions of the circus elephant water toy that form no part of the claimed design.

The dot-dash broken lines shown in the drawings depict portions of the circus elephant water toy that are magnified into enlarged views.

The dot-dash boundary lines demarcate claimed areas that have been enlarged for clarity while the lines themselves do not form part of the claimed design.
